GARMENT DISPLAY FORM

Samuel Messer, Rockaway Park, and George
Messer, Flushing, N. Y.

Application February 8, 1937, Serial No. 124,698

4 Claims. (Cl. 223—68)

This invention relates to garment display forms, and deals more particularly with forms upon which a garment may be effectively draped and displayed so as to present a pleasing and appealing silhouette to the observer.

In its generally broad aspect, the invention contemplates the provision of a form, simulating a considerable portion of the human torso, upon which the garment is arranged and having 10 preferably integral portions adapted to clamp, grip, or otherwise engage excess material of the garment so the front thereof is pleasingly draped to present a slender silhouette.

More specifically, the invention contemplates 15 a form which is moulded of a suitable material, substantially rigid in use, but which may be provided with resilient portions adapted to serve to engage excess material of a garment draped thereon in order to obviate the use of pins or 20 other such means which tend to mutilate the garment.

Other novel features of the invention reside 25 in the provision of a form adapted for interchangeable use in association with a display standard or any common form of garment hanger; in the convenient manner in which the form may be applied to a display standard; and in the several disclosed structural features which 30 will be more clearly apparent as the description of the invention progresses.

The mentioned and other pertinent objects, 35 features, and advantages are realized in the invention as disclosed in the accompanying drawing in which several preferred forms thereof are illustrated. While quite detailed, the drawing is intended only to disclose the invention in some of its aspects and does not exhaust the possible applications thereof.

In the drawing:

40 Fig. 1 is a rear perspective view of a garment form as at present contemplated and as mounted upon a display standard of usual design.

Fig. 2 is a top plan view of the form, the standard being shown in cross section.

45 Fig. 3 is a similar view of an alternate form of garment form.

Fig. 4 is a rear elevational view of another modified form of garment form and shown as suspended from a garment hanger.

50 Figs. 5 and 6 are plan views of other modified garment forms.

Fig. 7 is a rear perspective view of a form incorporating shoulder and neck portions.

Fig. 8 is a top plan view of still another modified 55 garment form.

The invention, as shown in Figures 1 and 2, comprises a garment form 11 which simulates the torso of the human body and has a vertical extent between the breasts and hips. However, in order to present a slim silhouette as viewed from the front, the periphery, as viewed from the top, is somewhat smaller than the similar normal dimensions of the human body. Hence, when a garment is fitted to the form, a considerable amount of excess material must be gathered together and neatly and painstakingly arranged at the back of the form. Heretofore, this was accomplished by means of pins or the like, and other haphazard means which made the fitting operation a cumbersome and tedious task. In 15 addition, the above makeshift means, caused mutilation of the garment which was thus rendered unfit for sale at the price for which it was made to retail. It is apparent that the losses thus incurred were considerable. 20

With the above in mind, the form 10 is provided with a slit as at 11. This slit may be arranged at the back, as shown, or may be along the side, or at any point of the form, other than the front. Since it is contemplated to make the form 25 of a substantially rigid yet pliable material such as fabric-covered fibre or the like, it is at once apparent that the slit 11 will at all times tend to remain closed but can readily be opened for the insertion therein of excess material. This 30 material is effectively gripped between the smooth, round edges 12 for the length of the form and in this manner the garment may be quickly and artistically fitted in a relatively short time and without injury to the garment material. In addition, the rear of the garment will 35 be presentable, which certainly was not the case when previous draping methods were employed.

As can be seen from Figure 3, the form, in addition to the slit 10, may be provided with one 40 or more clamping or gripping slits 13, preferably positioned near the sides of the form and each provided with a pocket portion 14 for the accommodation of garment material forced through said slits. In this form either the slit 11 or the 45 slits 13 may be used, or in some instances, both may be used.

As illustrated in Figure 4, the material of the form may be terminated along the spaced edges 15 and metallic or other suitable members 16 may 50 be fixed to the form to provide the coacting edges 12a—12a between which the slit 11a is formed. As shown, the members 16 are in spaced relation to provide plural gripping means but can be continuous if desired, in accordance with the 55

form shown in Figure 1. It will be noted that this form is shown as somewhat longer than the form in Figure 1 and it will be understood that either of these may be made of the length of the other or any other suitable length.

The form illustrated in Figure 5 has its slit 11^b directed laterally being formed between the overlapping portions 12^b—12^b of the body. This is a convenient type of construction since it is necessary to only flex one of the rear walls of the form to effectively tuck the material between the portions 12^b—12^b.

Fig. 6 illustrates still another form of the invention, being designed along the lines of the form shown in Figure 4. In this instance, the clamping members 16 are omitted to leave unobstructed the space between the edges 15 but adjacent these edges, the form is provided with gripping slits 13^a and pockets 14^a substantially similar to the construction of Figure 3. The gap between the edges 15, of course, is concealed by the garment fitted to the form.

Another variation of the invention is depicted in Figure 7 wherein the form is provided with a shoulder and neck upper portion 17, a gap 18 being provided to allow the form portion to function in the manner above described. As is apparent from the drawing, the form may be a complete usable device in itself and may be used for displaying girdles, brassières, corsets, etc., by merely being set upright upon a display counter or shop window floor.

As shown in Figure 8, the form may be continuous in contour with the slit 11 omitted. The gripping slits 13 may be positioned at the sides of the form as shown so that both the front and the back of the garment displayed thereon present a pleasing and undisturbed appearance.

When used in association with a display standard 20 such as shown in Figure 1, the form may be adjustably secured in relation to the garment hanger 21 by suitable means such as shown at 22 in Figures 1 and 2 and at 23 in Figure 3. In this connection, the slit 11 has an added function which is to facilitate mounting the form on the standard without necessitating the removal of the hanger 21. The resiliency of the form adjacent the slit effectively permits the form to be snapped past the standard so the securing means 22 or 23 may readily engage said standard. Similarly, removal of the form may be expeditiously accomplished. As shown in Figure 8, the lateral portions of the form are left free of any of the form supporting means which as shown, are affixed to the front and/or back thereof as by the means 22^a. In this manner, the form portions adjacent the slits 13 are free

to be flexed during insertion of material in the pockets 14.

The form may be supported by suspending it from the hanger 21 (as shown in Figure 4) as by bands, ribbons, or wires 24. In this type of mounting the hanger need not be necessarily carried by a standard but may be otherwise supported as by hanging it from a point from above.

While the invention is quite simple in its conception, it can be seen from the foregoing disclosure that it may be employed in many ways. For this reason, the prior art, rather than the present specific disclosure should form the basis of interpretation of the scope of the invention as claimed.

We claim:

1. A display form comprising a hollow body simulating a portion of the human torso, said body having a substantially oval contour as viewed from the top and provided with substantially parallel spaced edges to form an uninterrupted space in the rear of the form extending from top to bottom thereof, and means fixed to said form at said edges comprising reentrantly bent portions constituting coacting gripping jaws between which excess material of a garment draped on the form may be tucked for yielding retention thereby.

2. A display form comprising a tubular body having a front garment displaying portion and edge portions at the rear thereof directed toward each other, the contiguous edges of said latter portions being inturned to constitute gripping portions for gripping the rear of a garment draped on the form.

3. A display form comprising a tubular body of flexible sheet material formed to simulate a portion of the human torso, said body having vertical edges which are disposed adjacent each other at the rear of the form and inturned to present coacting curved gripping jaws, the curved edges of the gripping jaws being resiliently yieldable to receive and yieldably retain between them excess material of a garment draped on the form.

4. A display form comprising a tubular body simulating a portion of the human torso, said body being oval in contour as viewed from the top and formed at the rear with cooperating portions having normally contiguous edges, said portions being adapted to be flexed to separate said edges to receive and to grip therebetween excess material of a garment draped on said form.
